UNITED STATES PATENT OFFICE

1,988,506

DIE-CASTING MACHINE

Charles Pack, Jackson Heights, N. Y.

Application January 15, 1932, Serial No. 586,857

7 Claims. (Cl. 22—68)

This invention relates to die-casting, and more particularly to a novel form of die-casting machine.

The primary object of the present invention, generally, is to provide an improved die-casting machine which will be relatively simple in construction, and which will operate efficiently over an exceptionally long period of useful life for the production of perfect die-castings.

More particularly, some of the objects of the present invention are to permit the casting of any metal at any desired pressure, regardless of the melting point of the metal and of the intensity of the casting pressure desired; to permit the casting of the desired metal in a pure state, uncontaminated by the gradual solution therein of the metal of the machine parts; to permit the casting of a variety of metals and alloys; and to permit readily changing over from one metal to another without difficulty during the operation of the machine. In a general way, it may be stated that the foregoing objects are fulfilled by utilizing in the die-casting machine a cup or receptacle into which or out of which a pressure plunger may be reciprocated in order to eject a single charge of molten metal, previously ladled into the cup, from the cup to the die.

Further and more particular objects of the present invention in connection with the general type of machine heretofore outlined are, first, to prevent flow of molten metal into the die prior to the application of pressure by means of the pressure plunger; and secondly, to insure removal from the apparatus of waste metal.

In accordance with the present invention, premature flow of molten metal into the die is prevented by means of a valve; and further objects of the present invention are to simplify the necessary valve mechanism; to use the gate post of the die-casting machine as the valve mechanism; to retain the usual desirable functions of the gate post, such as aiding in the uniform distribution of metal flowing into the die, and subsequently helping removal of solidified metal from the flow passage or gate; to simplify controlling the necessary mechanical movements of the combined gate passage valve and gate post; and, in the case of hydraulically operated mechanism, to dispense with the necessity of providing additional or special valves for controlling the reciprocable gate post mechanism.

To the accomplishment of the foregoing and such other objects as may hereinafter appear, my invention resides in the die-casting machine

elements and their relation one to the other as hereinafter are more particularly described in the specification and sought to be defined in the claims. The specification is accompanied by a drawing, in which:

Fig. 1 is a partially sectioned side elevation of one form of die-casting machine embodying features of the present invention;

Fig. 2 is a similar elevation of a portion of the machine, illustrative of a different stage in the operation of the machine;

Fig. 3 is an enlarged bottom view of the end of the pressure plunger; and

Fig. 4 is illustrative of the solidified residue obtained from the cup.

Referring to the drawing, and more particularly to Fig. 1 thereof, the die-casting machine of the present invention comprises, generally, a cup or receptacle C, a reciprocable plunger P adapted to be reciprocated into and out of the cup C, a die D, a flow passage or gate G leading from the cup C into the die D, a reciprocable gate post or rod R adapted to act both as a valve for the flow passage or gate G and as a gate post, and knock-out means K for knocking from the end of plunger P the solidified residue drawn from cup C.

In operation, briefly, a measured charge of molten metal sufficient for a single casting operation is poured or ladled from a separate heating crucible, not shown, into the cup C. Plunger P descends and forces or ejects the molten metal from the cup C into the die D. Plunger P is then retracted, and the die D is opened in order to separate the gate from the solidified residue of metal remaining in cup C, and thereby to permit removal of the residue from the cup, as well as removal of the finished casting from die D. The die is then closed, a new charge of molten metal poured into the cup, and the casting operation repeated.

It will immediately be noticed that because of the relation of the cup C to the die D, the molten metal poured into the cup C may tend to flow directly into the die D even before the pressure plunger P descends. This is highly undesirable because such metal will tend to solidify in the die before it is placed under pressure, and will cause the finished casting to be porous and non-uniform in texture. In accordance with one feature of the present invention, valve means is provided to prevent premature flow of metal from the cup into the die. This valve means is here exemplified by the rod R the tapered end of which is reciprocable into the gate passage G and serves to retain the molten metal in the cup. When pressure

plunger P descends, however, the rod R may be retracted to permit the desired flow of metal. Preferably, the valve is forced open by the pressure of the molten metal, for in this manner the metal is injected instantaneously and forcibly into the complete mold, so that all of the metal in the casting is compressed and cooled under uniform conditions. In the present case it is preferred to use the gate post also as the valve means, so that the rod R further functions, even in its retracted position as shown in Fig. 2, as a gate post and fulfills the usual desirable functions of such a post, as, for example, to help uniformly distribute the injected metal around the mold, and to subsequently help removal of the solidified metal from the gate passage G with the casting when the die is opened.

Considering the machine in greater detail, the die D preferably consists of a stationary or cover portion 2, and a movable or ejector portion 4. The cover portion 2 is fixed to a stationary platen 6, while the movable portion 4 is fixed to a movable platen 8. The latter may be reciprocated by suitable means, here exemplified by hydraulic piston 10, reciprocable in a cylinder 12. The cylinder may be mounted on a pedestal 14, only a portion of which is shown, and the reaction of the extreme force applied to piston 10, in order to keep die D closed during the casting operation, may be taken by tension rods 16 extending between platen 6 and the cylinder 12. These rods may also be used as guide rails for the reciprocable platen 8.

In order to simplify the valve mechanism needed to control piston 10, pipe 18, leading into one end of cylinder 12, may be continuously connected to a source of high pressure fluid, while pipe 20, connected to the head end of cylinder 12, may be alternatively connected to either the source of high pressure fluid or a low pressure exhaust tank through an intermediate control valve. The piston rod 22, connected between movable platen 8 and piston 10, may be made very large in diameter, so that only a relatively small force will be exerted when opening the die, which force is directly opposed and overcome by the large force exerted when pressure fluid is admitted to pipe 20 in order to close the die.

The reciprocable gate post R may be controlled by mechanical means, but is here exemplified as being controlled by hydraulic piston 24 and cylinder 26. Cylinder 26 is mounted in end to end relation with cylinder 12, and is made of sufficient length to permit the desired valve reciprocation of rod R in addition to its reciprocation with ejector die 4 while acting as a gate post. The gate post rod R is connected to piston 24 by a piston rod 32, and this rod is preferably made coaxial with the main piston and cylinder mechanism 10, 12 and extends completely therethrough, as is shown in the drawing, to the auxiliary piston and cylinder mechanism 24, 26.

In operation, it will be understood that when die D is closed, the gate post R is advanced or projected into the gate passage G, thereby sealing the cup C from die D when molten metal is poured into the cup C. During the casting operation, the gate post may be retracted by appropriate valve mechanism controlling the flow of fluid to the auxiliary piston and cylinder mechanism. This valve mechanism may permit of further reciprocation of the gate post with the die when the die is opened. However, for the sake of simplicity and in order to dispense with the necessity of separate control valves for the auxiliary piston and cylinder mechanism, the latter may be con-

nected directly in parallel with the main piston and cylinder mechanism, as shown in the drawing, that is, the head end of cylinder 26 may be connected by means of a pipe 28 to the head end of cylinder 12 or to pipe 20, while the other end of cylinder 26 may be connected by means of a pipe 30 to the corresponding end of cylinder 12 or to the pipe 18. Only a small force is needed for the retraction of gate post R with the die 4 when the die is opened, and accordingly piston 24 is made only slightly larger in diameter than the piston rod. Furthermore, only a relatively small force is needed to advance the gate post R into the gate passage G at the beginning of the casting operation, and this force upon the head end of piston 24 need only be a little greater than the return force applied to the other side of piston 24. This ordinarily should be made possible by the use of a small diameter piston rod 32 between piston 24 and gate post R, together with a piston 24 which is only slightly larger in diameter than the piston rod 32. However, even if piston rod 32 is made of large diameter, the desired force may be obtained by using a tail rod 34 extending from the head end of piston 24, as is shown in the drawing, thereby reducing the effective area of piston 24. Tail rod 34 will, of course, be somewhat smaller in diameter than piston rod 32. Preferably the dimensioning of the parts should be made such as to dispense with the use of the tail rod 34, because this adds considerably to the over-all length of the machine.

With the arrangement shown, it will be understood that when pressure fluid is admitted to pipe 20, die D is closed and at the same time the gate post R is advanced not only along with the ejector die 4, but is further projected into the gate passage G in order to seal the passage. When pressure plunger P descends, an extremely high pressure is applied to the molten metal in cup C, and this pressure forcibly pushes gate post R back until a stop collar 36 on the gate post bears against a stationary part of platen 8, as is best shown in Fig. 2. After the casting shot has been taken, pipe 20 is connected to exhaust, whereupon the pressure applied through pipe 18 causes the ejector portion 4 of die D to open, and at the same time causes the gate post R to move back with the die. Ejector mechanism in the ejector portion 4, which mechanism may be conventional and is not shown, then serves to eject the finished casting from the die. This arrangement dispenses with the use of special valves for controlling the auxiliary piston and cylinder mechanism, and at the same time has the advantage of securing a sudden and instantaneous injection of the complete charge of molten metal into the die, for the gate post R is not forced rearwardly out of gate passage F until considerable pressure is developed within receptacle C.

The pressure plunger P may be operated by any preferred means, here exemplified by hydraulic piston and cylinder mechanism generally indicated at 40. The cylinder 40 is mounted on a frame 42 which extends downwardly to the foundation of the machine and intermediately includes the stationary head 6 previously referred to. The ends of cylinder 40 may be connected for fluid flow by pipes 44 and 46; and here again, in order to simplify the valve mechanism, the area of the lower side of the piston may be made relatively small, and pipe 46 may be constantly connected to the source of high pressure fluid. Pipe 44 may then be connected to either the

source of high pressure fluid or an exhaust tank through an appropriate valve. The valve in pipe 44 is properly related to the valve in pipe 20 to insure closing of the die D prior to the pressure stroke of the plunger P, and, for reasons subsequently explained, to insure elevation of the plunger P prior to opening of the die D.

The solidified residue of metal in cup C at the end of the casting operation is preferably forced upwardly before die D is opened, in order to shear the said residue from the gate G at the point of minimum diameter. In some cases, particularly with a very small gate opening at the cup, it may be possible to first open the die D and separate the metal in gate G from the residue in cup C by a direct pull in tension. This, however, is a relatively undesirable sequence of operation, first, because it requires undue hold by ejector die 4 on the casting therein; and second, because there is no perfect assurance that the point of separation will take place flush with the wall of the cup.

In order to simplify the machine and to dispense with special mechanism for ejecting the solidified residue from cup C, the plunger P of the present machine is preferably provided with appropriate recesses, undercuts, or slots suitably shaped to cause the residue of metal in the cup to be retracted along with the plunger. In the particular embodiment here shown, this means consists simply of the transverse dovetail-shaped slot 50 at the bottom of the plunger. This slot, incidentally, is located near the gate opening, and therefore provides a shearing force at the point where it is most needed. As is most clearly shown in Fig. 3, the slot 50, while made dovetailed in cross section throughout its length, is tapered in its longitudinal direction, that is, from the end 52 to the end 54, in order to facilitate subsequently knocking the solidified residue from the end of the plunger. This residue, as is best shown in Fig. 4, is generally in the form of a disc, pancake, or biscuit 56 surmounted by a dovetailed member 58 complementary to the slot 50. It is obvious that by hitting this residue in the direction from the point 54 to the point 52 in Fig. 3, it may readily be separated from the end of the plunger. The pancake-shaped residue of metal may be made relatively thin in order to economize in the use of material and fuel, and in such case the end 54 of slot 50 provides additional thickness of residue metal which may be struck when knocking the residue from the plunger.

In order to knock the residue from the end of the plunger, knockout means is preferably provided, consisting of a hammer-like element 132 carrying a knockout bar 134. These elements are reciprocable and preferably adjusted to strike the residue on the end of the plunger when the plunger is in retracted position. The desired movement may most simply be obtained by suspending the elements 132 and 134 on an arm 136 pivoted at 132 on brackets 140 mounted on the machine frame. This knockout mechanism may be operated manually after each stroke of the plunger, or, if preferred, may be operated automatically, and means for automatic operation is schematically shown in Fig. 1 of the drawing. This means consists simply of a projecting bell 138 and crank arm 142 rigidly secured to the arm 136 and interposed in the path of a collar 144 mounted on plunger P. The position of collar 144 is adjustable, as also are the positions of element 132 and the knockout bar 134. These various members are so relatively positioned that

knockout bar 134 is moved against the residue at the end of the plunger at or near the end of the upward stroke of the plunger. It will be understood, of course, that the knockout means here shown is merely by way of exemplification, and that more complex mechanical movements may be used for the same purpose.

The operation of the machine may now be briefly summarized. A measured charge of molten metal is transferred from a crucible or melting furnace to the cup C. Plunger P then descends, and after developing a certain amount of pressure, overcomes the resistance of valve R and forces the same rearwardly until its movement is arrested by collar 36. At the same time, the charge of molten metal is forcibly ejected into the die D.

Plunger P is then retracted, causing the residue of solidified metal in the cup to shear free from the metal in gate G, and at the same time retracting the residue of metal with the plunger. During the upward movement of plunger P, the die D may be opened, the movable portion 4 of the die carrying with it the casting and the conical core of metal from gate G. Gate post R also moves back with the ejector portion 4 of the die, and during this movement helps to withdraw the solidified metal from gate G. At or near the end of the upward stroke of plunger P, the solidified residue of metal on the end of the same is knocked free from the plunger, after which it may be remelted and again used. Near the end of the opening movement of the die, the casting and gate are ejected therefrom and removed. The die is then closed; gate post R is advanced into gate G, after which the cup or receptacle C is again ready to receive a fresh charge of molten metal. The complete cycle of operation may thus be repeated as often as desired.

The mode of constructing and using the die-casting machine of the present invention, and the many advantages thereof will, it is thought, for the most part be apparent from the foregoing description. The parts of the machine are not immersed in molten metal, thereby preventing solution and increasing the life of the machine and making it possible to cast with pure rather than contaminated metal. The machine makes it possible to cast any metal at any desired pressure, the metal being heated in a separate and preferably refractory crucible. The metal being used for casting purposes may be changed in an instant by simply beginning to ladle metal from a different crucible. No metal is permitted to flow into the die until the entire body of metal is forcibly ejected from the cup into the die, and this prevents flaws, porosity, and other defects. This desirable result is accomplished by the use of valve means of a simple type, and the valve means may itself be or be used as the gate post of the die. This post, in addition to its valve functions, retains all of the usual advantages and functions of a gate post. The necessary movements of the combined valve and gate post are obtained without necessitating additional valves for controlling the over-all operation of the machine. The solidified residue of metal in the cup is removed therefrom in a simple and efficient manner, and without the provision of special mechanical means with attendant complication, although such special ejector means may, if desired be used. The residue is preferably removed with the plunger, and when so removed, is readily knocked from the plunger either manually or automatically.

It will be apparent that while I have shown and described my invention in preferred form, many changes and modifications may be made in the structure disclosed, without departing from the spirit of the invention, defined in the following claims:

I claim:

1. In a die-casting machine, a die, a gate or flow passage leading into said die, said passage being substantially larger in cross-section at its discharge end than at its inlet end, a reciprocable gate post in said die, said gate post being substantially smaller in cross-section than the discharge end of the passage, in order to freely permit flow of metal through the passage around the gate post and into the die cavities, when the gate post is in normal position, and means for reciprocating said gate post between projected and retracted positions, the projected position advancing the gate post into the small inlet end of the gate passage in order to act as a valve to prevent premature flow of metal into the die, and the retracted position being the normal gate post position.
2. A die-casting machine comprising a vertical cylindrical pressure cup for receiving a charge of molten metal sufficient for a single casting operation, a vertically reciprocable plunger arranged to reciprocate into and out of said cup, a horizontally separable die located alongside of said cup, a gate or flow passage interconnecting the lower portion of the cup and the die, said passage being substantially larger in cross-section at its discharge end than at its inlet end, a horizontally reciprocable gate post in said die, said gate post being substantially smaller in cross-section than the discharge end of the passage, in order to freely permit flow of metal through the passage around the gate post and into the die cavities, when the gate post is in normal position, and means for projecting said gate post into the small inlet end of the gate passage in order to act as a valve to prevent premature flow of metal from the cup into the die.
3. A die-casting machine comprising a pressure cup for receiving a charge of molten metal, a reciprocable plunger arranged to reciprocate into and out of said cup, a die located near said cup, a gate or flow passage interconnecting the lower portion of the cup and the die, said passage being substantially larger in cross-section at its discharge end than at its inlet end, a reciprocable gate post in said die, said gate post being substantially smaller in cross-section than the discharge end of the passage, in order to freely permit flow of metal through the passage around the gate post and into the die cavities, when the gate post is in normal position, means for controlling the reciprocation of said gate post in order to project the same into the small inlet end of the gate passage prior to the casting operation and to permit withdrawal of the same from the gate passage during the casting operation, and means to remove the solidified residue from the cup including undercut recesses at the end of the plunger and knockout means for knocking the residue from the end of the plunger after the plunger has been retracted from the cup.
4. A die-casting machine comprising a pressure cup for receiving a charge of molten metal, a plunger arranged to reciprocate into and out of said cup, a separable die located near said cup, a main hydraulic piston and cylinder mechanism for opening and closing said die, a gate

or flow passage interconnecting the lower portion of the gate and the die, said passage being substantially larger in cross-section at its discharge end than at its inlet end, a combined reciprocable gate passage valve and gate post located in said die, said gate post being substantially smaller in cross-section than the discharge end of the passage, in order to freely permit flow of metal through the passage around the gate post and into the die cavities, when the gate post is in normal position, auxiliary hydraulic piston and cylinder mechanism connected to said reciprocable gate post for projecting the same into the small inlet end of the passage to close the same, and means controlling the sequence of operation of said main and auxiliary piston and cylinder mechanisms to prevent premature flow of metal from the cup to the die.

5. A die-casting machine comprising a pressure cup for receiving a charge of molten metal, a plunger arranged to reciprocate into and out of said cup, a separable die located near said cup, a main hydraulic piston and cylinder mechanism for opening and closing said die, a gate or flow passage interconnecting the lower portion of the gate and the die, said passage being substantially larger in cross-section at its discharge end than at its inlet end, a combined reciprocable gate passage valve and gate post located in said die and extending axially through the aforesaid hydraulic piston and cylinder mechanism, the end of said gate post being substantially smaller in cross-section than the discharge end of the passage, in order to freely permit flow of metal through the passage around the gate post and into the die cavities, when the gate post is in normal position, auxiliary hydraulic piston and cylinder mechanism connected to said reciprocable gate post for projecting the same into the small inlet end of the passage to close the same, and means suitably interconnecting said main and auxiliary piston and cylinder mechanisms.

6. A die-casting machine comprising a cylindrical pressure cup for receiving a charge of molten metal sufficient for a single casting operation, a vertically reciprocable plunger arranged to reciprocate into and out of said cup, a horizontally separable die located alongside of said cup, a main hydraulic piston and cylinder mechanism for opening and closing said die, a horizontal gate or flow passage interconnecting the lower portion of the gate and the die, said passage being substantially larger in cross-section at its discharge end than at its inlet end, a reciprocable gate post located in said die and extending axially through the aforesaid hydraulic piston and cylinder mechanism, the end of said gate post being substantially smaller in cross-section than the discharge end of the passage, in order to freely permit flow of metal through the passage around the gate post and into the die cavities, when the gate post is in normal position, auxiliary hydraulic piston and cylinder mechanism connected to said reciprocable gate post, means connecting the said main and auxiliary hydraulic piston and cylinder mechanisms in parallel whereby the gate post is reciprocated into the small inlet end of the gate passage when the die is closed and is retracted when the die is opened, the area of the auxiliary piston being relatively slight in order to permit an initial retraction of the gate post under casting pressure, and means to limit the aforesaid initial retraction.

7. A die-casting machine comprising a pressure cup for receiving a charge of molten metal suff-

lient for a single casting operation, a vertically reciprocable plunger arranged to reciprocate into and out of said cup, a separable die located near the cup, a main hydraulic piston and cylinder mechanism for opening and closing said die, a flow passage interconnecting the lower portion of the cup and the die, a reciprocable valve post located in said die and extending axially through the aforesaid piston and cylinder mechanism, auxiliary hydraulic piston and cylinder mechanism connected to said reciprocable valve post, means connecting the said main and auxiliary hydraulic piston and cylinder mechanisms in paral-

lel whereby the valve post is reciprocated into the passage when the die is closed in order to prevent premature flow of molten metal from the cup into the die, the area of the auxiliary piston being relatively slight in order to permit the valve post to be readily forced back under casting pressure to open the passage, means to limit the opening movement of the valve post, and means to remove the solidified residue from the cup and to simultaneously separate the said residue from the additional solidified residue of metal in the passage at the end of the casting operation.

CHARLES PACK.
